UNITED STATES PATENT OFFICE.

CHARLES J. CRONK, OF CLIFTON PARK, NEW JERSEY, ASSIGNOR TO E. I. DU PONT DE NEMOURS POWDER COMPANY, OF WILMINGTON, DELAWARE, A CORPORATION OF NEW JERSEY.

DESIGN FOR FABRIC FOR CAR-CURTAINS.

46,275.

Specification for Design.

Patented Aug. 18, 1914.

Application filed August 22, 1913. Serial No. 786,167. Term of patent 14 years.

To all whom it may concern:

Be it known that I, CHARLES J. CRONK, a citizen of the United States, residing at Clifton Park, in the county of Hudson and State of New Jersey, have invented a new, original, and ornamental Design for Fabric for Car-Curtains, of which the following is a specification, reference being had to the accompanying drawing, forming part thereof.

The figure is a plan view of a portion of

a fabric for car curtains, illustrating my new design.

I claim:

The ornamental design for a fabric for car curtains, as shown.

CHARLES J. CRONK.
